Primary Examiner — Sheryl Lane*Assistant Examiner* — Stacey L Hopkins(74) *Attorney, Agent, or Firm* — JCIPRNET(57) **CLAIM**

The ornamental design for a handheld floodlight, as shown and described.

DESCRIPTION

FIG. 1 is a perspective view of a handheld floodlight showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is a perspective view thereof with the light emitting portion rotated.
The broken lines show unclaimed portions of the article and form no part of the claimed design.**1 Claim, 6 Drawing Sheets**(56)
